STRAND TREATING APPARATUS

Richard L. Fearn, Rockville, Md., assignor to
 Syncro Machine Company, Newark, N. J., a
 corporation of New Jersey

Application January 19, 1939, Serial No. 251,759

3 Claims. (Cl. 266—3)

The general object of this invention is the provision of a simplified mechanism by means of which a heated strand, particularly a wire strand, may be subjected to a chemically active vapor.

Other and more detailed objects of this invention will be apparent from the following detailed description of one embodiment thereof.

This invention resides substantially in the combination, construction, arrangement, relative location of parts, all as will be explained in detail below.

The single figure of the drawing is a vertical, central, longitudinal, cross-sectional view through the wire treating device of this invention showing portions of associated mechanism with which this invention is not concerned.

As will be seen from the drawing, the strand W passes through an aperture in a plate 51 upon which aperture is played a flame from a small burner 52. This burner is supplied with a gaseous fuel mixture in any suitable manner not shown. The plate 51 is very important, in that it is a massive block of metal arranged so that its temperature, notwithstanding the fact that the flame 52 plays thereon, remain low. By reason of the fact that the plate is relatively massive, and is arranged so as to lose heat readily, it remains at a relatively low temperature notwithstanding the fact that the flame 52 plays thereon. Preferably, in the case of copper strands this block or plate 51 should be made of steel. In the case of brass strand it is preferably made of chrome iron or chrome steel. The flame blowing on this relatively cold plate produces hydrogen and water vapor. The strand W after being heated in a nonoxidizing atmosphere, passes directly from the zone of heating (not shown) into and through the aperture in plate 51.

This arrangement has the advantage of excluding air and oxidizing atmospheres from the wire by flooding the aperture in the plate 51 with the products of combustion, which as indicated in the drawing, are introduced into the chlorinating chamber 50. The introduction of these gases is facilitated in a manner about to be described.

The strand W passes through a pair of guide extensions 54 on the lower end of a thermo-couple support 53 which forms no part of this invention.

The wire then passes into an inner chamber 51 in the casing 50 which is shown as made of glass and supported in any suitable manner.

The entering end of the glass chamber has a conical aperture which continues into a cylindrical portion and the discharge end has a cylindrical aperture of a conical portion, both of which apertures are large enough so that the wire passes freely therethrough. At 62 is a chlorine supply pipe extending from any suitable source of dry, pure chlorine gas. This pipe opens into the inner chamber 51. Mounted on top of the casing 50 within a housing 64 is a tube 63, the lower end of which is open to the interior chamber 51, and the upper end of which opens to the atmosphere. Surrounding the tube is a heater 65 which is illustrated as an electric heater having the current supply leads 66. A similar arrangement comprising a tube 67 is open at its lower end to the casing 50 and at its upper end to the atmosphere. It is enclosed within a housing 68 which contains an electric heater 69 provided with the current supply lead 70. These devices operate to maintain a slightly sub-atmospheric pressure condition within the chambers 50 and 51. The heaters cause convection currents which result in the slow removal of vapors from the respective chambers through the upper ends of the tubes 63 and 67, insuring the gases generated in the aperture of plate 51 will flow into the chambers 50 and 51. The chlorine gas supplied through the pipe 62 is supplied in rather small quantities at a pressure just sufficiently high to insure its introduction into the chamber 51.

The heated strand W which is at a temperature in the neighborhood of 300 degrees Centigrade, in passing through the chamber 51 is exposed to the gas which serves to form fluxing salts which facilitate the application of the coating to the strand. In order to facilitate this action, products of combustion from chamber 50 are drawn through end apertures of chamber 51 by reason of the reduced pressure caused by suction in tube 63 and mixing with the chlorine gas, greatly intensifying the reactions. A heater 71 with the current lead 72 acts to maintain the temperature within the chamber 50 in the neighborhood of 212 degrees Fahrenheit, in order to prevent condensation of vapors.

The reference numeral 73 generally indicates the coating apparatus which has been illustrated for the purpose of showing one possible treatment of the wire after fluxing. The details of the coating apparatus form no part of this invention.

From the above description it will be apparent to those skilled in the art that many modi-

fications in the details of structure employed carrying out the novel subject matter of this disclosure, may be made without departing from the novel teaching herein. I do not, therefore, desire to be strictly limited to the disclosure as given for purposes of illustration, but rather to the scope of the claims granted me.

What is claimed is:

1. A processing device for treating heated strands moving therethrough in the direction 10 of their length including a closed chamber having end walls, the end wall at the entering end of the chamber comprising a relatively massive metal plate having an aperture through which the strand moves, and means for playing an 15 open flame on said aperture.

2. A processing device for fluxing heated strands moving therethrough in the direction of their length, including a closed chamber having end walls, the end wall at the entering end of 20 the chamber comprising a relatively massive

metal plate having an aperture through which the strand moves, means for playing an open flame on said aperture, means forming an inner compartment within said chamber through 5 which the strand passes, and means for delivering small quantities of chemically active vapor into said compartment.

3. A processing device for treating heated strands moving therethrough in the direction of their length, including a closed chamber having end walls, the end wall at the entering end of the chamber comprising a metal plate having an aperture through which the strand moves, means for playing an open flame on said aperture, means forming an inner compartment within said chamber through which the strand passes, means for delivering small quantities of an active vapor into said compartment, and means for slowly withdrawing the vapors from 25 said chamber.
